ABSTRACT: Currency counting apparatus including a pair of independently rotatable shafts mounted in axial alignment with first ends thereof being adjacent, and each including a pair of gear elements rotatably mounted thereon. Each pair of gear elements is in meshing engagement with a pinion fixedly mounted to a respective shaft. Gear members mounted at the first ends of each of the shafts are in meshing engagement with pinions attached at the inner perimeter of a ring gear member. The ring gear member is mounted between and is coaxial with the gear members, and is connected to a register for totaling the deposit of currency received in a currency receiving mechanism. The ring gear member constantly has a driving force imposed thereon. For each deposit of a particular denomination of currency, a corresponding gear element is permitted to rotate a corresponding predetermined number of degrees on a respective shaft. The rotation thereof allows a corresponding pinion to rotate, thereby permitting rotation of the corresponding shaft, all under the influence of the driving force on the ring gear member, which causes the operation of the register. Each gear element is operated by a pawl and solenoid arrangement and is stepped according to the deposit of currency. A self-restoring rewind mechanism, connected to the ring gear member is provided to keep the counter operable at all times.

CASH VALUE ACCUMULATOR

BACKGROUND OF THE INVENTION

This invention relates generally to devices for counting currency and more particularly to a counter for totaling the amount of cash received in coin or the like operated devices.

Various types of coin counters are now in use for totaling the amount of cash taken into coin operated devices, such as, for example, coin operated phonographs, commonly called "juke boxes." (Note that there are now mechanisms available for accepting dollar bills, and these are contemplated under the following discussion as but one more slot in a "coin" mechanism.) One such counter can be found in U.S. Pat. 3,333,769, by the inventor of the subject invention. While these counters are satisfactory in most ways, they are not able successfully to register the entry of a pair or more of coins dropped into the phonograph coin receiving mechanism simultaneously. The existing coin counters normally will register the larger of the coins but will not simultaneously register the smaller ones. The speed of operation of existing coin counters is limited and too-rapid insertion of coins can result in registering less than the total value of all of the coins deposited. This causes discrepancies between the amount of cash registered and that actually received in the coin receptacle of the device.

SUMMARY OF THE INVENTION

Accordingly, it is a general object of this invention to provide a new and improved, accurate currency counting or cash value accumulating apparatus.

It is a more specific object of this invention to provide a new and improved currency counter, for use in coin operated phonographs or the like devices, which registers all coins dropped into the device, whether they are dropped separately, either slowly or in rapid succession, or simultaneously.

DESCRIPTION OF THE DRAWINGS

A better understanding of the present invention and its organization and construction may be had by referring to the description below in conjunction with the accompanying drawings, wherein:

- FIG. 1 is an over-all perspective view of a preferred embodiment of a currency counter or cash value accumulator according to the invention;
- FIG. 2 is a perspective view of a portion of the counter embodiment of FIG. 1, illustrating an alternative manner of connecting a counting meter or register thereto;
- FIG. 3 is a cross-sectional view of a portion of the embodiment of FIG. 1, taken along the line 3-3 thereof;
- FIG. 4 is an axial sectional view of the counting mechanism of the counter embodiment of FIG. 1, taken along the line 4-4 thereof;
- FIG. 5 is a plan view of the counting mechanism of the counter embodiment of FIG. 1;
- FIG. 6 is a cross-sectional view of the counting mechanism of FIG. 4, taken along the line 6-6 thereof;
- FIG. 7 is a cross-sectional view of the counting mechanism of FIG. 4, taken along the line 7-7 thereof;
- FIG. 8 is a cross-sectional view of the counting mechanism of FIG. 4, taken along the line 8-8 thereof;
- FIG. 9 is a cross-sectional view of the counting mechanism of FIG. 4, taken along the line 9-9 thereof;
- FIG. 10 is a cross-sectional view of the counting mechanism of FIG. 4, taken along the line 10-10 thereof;
- FIG. 11 is a cross-sectional view of the counting mechanism of FIG. 4, taken along the line 11-11 thereof;
- FIG. 12 is a side-sectional view of the rewind mechanism of the counter embodiment of FIG. 1;
- FIG. 13 is an axial sectional view of the winding mechanism of FIG. 12, taken along the line 13-13 thereof;
- FIG. 14 is a cross-sectional view of the winding mechanism of FIG. 12, taken along the line 14-14 thereof;
- FIG. 15 is a cross-sectional view of the winding mechanism of FIG. 12, taken along the line 15-15 thereof; and

FIG. 16 is a schematic diagram of a control circuit for a cash value accumulator according to the invention, which includes means for enabling the counting by the accumulator of currency other than coins.

DETAILED DESCRIPTION

Referring to the drawings more in detail, a preferred embodiment of a currency counter 20 is shown in FIG. 1 thereof. The counter 20 as shown in FIG. 1 includes two major portions, the first being the counting mechanism 22 and the second being the drive or winding mechanism 24. The counting mechanism 22 of the counter 20, as can be seen in FIG. 1, includes four vertical support members 26, 28, 30 and 32, a first pair 26 and 28 of which has mounted in aligned apertures, such as 34, therein a rotatable half-shaft 36. The second support member pair 30 and 32, likewise supports in aligned apertures therein a rotatable half-shaft 38. The two half-shafts, as can be seen in FIG. 4, are in axial alignment with each other with the inwardly facing ends 40 and 42, respectively, thereof being adjacent one another. Radially disposed stub shafts or mounting members 44 and 46 are fixed on half-shafts 36 and 38, respectively, between supports 26, 28 and 30, 32 by means such as set screws 48 and 50. Pins 52 and 54 extend from the ends of stub shafts 44 and 46 radially of half-shafts 36 and 38, and pinions 56 and 58 are rotatably mounted thereon, being held by means such as washers and retaining rings or C-washers, as shown.

Mounted on each of the half-shafts 36 and 38, on either side 30 of respective pinions 56 and 58 so as to mesh therewith, are pairs of bevel gears 62 and 64, and 66 and 68, respectively. The manner of mounting these gears is illustrated clearly in FIGS. 4 and 7 wherein gear 64 can be seen on half-shaft 36, with pinion 56 mounted on stub shaft 46 and engaging the teeth of the gear. As will be noted in FIG. 4, the bevel gears are not fixed to the respective half-shafts, but are mounted so as to be able to rotate thereon independently of the rotation of the half-shaft. Each of the bevel gears 62, 64, 66 and 68 includes, extending outwardly from the flat surface opposite the teeth portion thereof and near the outer perimeter, a number of pins or pegs 70. The pegs are angularly spaced about the respective gears and are adapted to be engaged by pawls 72 (FIGS. 1, 5, 6, 8 and 11), one of which is associated with each of the bevel gears and which is pivotally mounted on a respective one of the support members 26, 28, 30 and 32. Each of the pawls is connected to a spring 74 which causes the pawl normally to engage one of the pegs 70 of the associated gear. Solenoids 60 are connected respectively to the pawls to withdraw them against the force of springs 74. (In the drawings the pegs are shown as fixed in plates secured to the back surfaces of the gears. It is contemplated that in production the gears and plates, and perhaps also the pegs, would be formed integrally, such as by a plastic molding operation.)

Referring to FIGS. 6, and 8 through 10, there are shown therein, respectively, each of the gears 62, 64, 66 and 68, and the respective springs 74 and pawls 72 engaging the pegs 70 mounted thereon. Each of the pawls 72 includes a pair of arms 73 and 75, and each arm includes a tooth 77 and 79, respectively. The tooth 79 of arm 75 normally engages one of the peg members 70 of the particular gear, as shown in FIGS. 8, 10 and 11, and is held in engagement therewith by means of spring 74. The other tooth 77 acts as an overthrow stop, as indicated in FIG. 6, so that the gear element is able only to turn 60 the distance between consecutive pegs in one operation. Arm 75 of the pawl is connected to solenoid 60 via pull rod 81. The denomination of the currency with which the gear element is to be associated determines the number of pegs 70 included on a gear. For example, gear 62 includes ten equally arcuately spaced pegs 70; thus, the currency which it counts, in the embodiment shown herein, is five cent pieces, moving one peg for each five cent piece received; correspondingly, gear 64 has five pegs and corresponds to ten cent pieces, while gear 66 has two pegs and corresponds to twenty-five cent pieces; and gear element 68 includes only one peg, thus, counting fifty cent

pieces, turning one-half revolution each time a half dollar is received. While devices such as coin operated phonographs normally receive only coins, the currency counter according to the invention will also count dollar bills which may be received thereby. This will be explained hereinafter in referring to FIG. 16 of the drawings.

At the free ends 40 and 42 of the half-shafts 36 and 38, between the center support members 28 and 30, there is mounted another pair of bevel gears 76 and 78, respectively. Each of the gears 76 and 78 is fixedly mounted to a respective half-shaft member by means of screws 80 and 82, respectively.

A ring gear 90 (FIGS. 1, 4 and 9) having peripheral teeth is mounted coaxially with the gear elements 76 and 78 by means of a pair of pinions 84 and 86 mounted at the inner perimeter 88 of the ring gear and 180 degrees apart. Pinions 84 and 86 are rotatably mounted by means of radially inwardly directed pins 85 and 87, respectively, at the inner perimeter 88 of the ring gear 90, the pinions meshing with the gear element 78. Pinions 84 and 86 are adapted to mesh with both of the bevel gears 76 and 78, so that ring gear 90 is rotatable about the half-shafts with either or both of gears 76 and 78.

It will be noted that the gear elements used in the counter 20 according to the invention, are preferably constructed of a one-piece polymeric material such as nylon. This does not preclude, however, the use of gear elements which are not of a one-piece construction.

The drive or winding mechanism 24 of the currency counter 20 according to the invention, as shown in FIGS. 1 and 12, includes a rotatable shaft 92. A hub 93 is free to rotate on this shaft and a gear 94 which meshes with the ring gear 90 of the counting mechanism 22 of the counter 20 is fixed on the hub.

The gear 94 is in meshing engagement with still another gear 96 which is connected through a shaft 98 to a register or meter 100 of known design for totaling the amount of currency received in the device, such as a coin operated phonograph in which the counter 20 is used. The register or meter 100 can be connected to counting mechanism 22 in a number of ways. An alternative manner in which this may be accomplished is shown in FIG. 2 of the drawings, and will be discussed hereinafter.

A plate 101 is likewise fixed to hub 93 and hence to gear 94. A cup-shaped housing 104 is mounted on a hub 108 and is fixed to a disc or plate 106 on the hub by means such as screws passing through the plate and threaded into the housing. Hub 108 is free to rotate on shaft 92. The housing is fixed to the plate 101 for rotation therewith by tabs 97 which extend through openings 95 in the plate (see also FIG. 3).

A helically wound spring 102, best seen in FIGS. 12 and 14, is mounted within housing 104 with the inner end of the spring received in a slot in the shaft and held by means of a screw 103. The radially outwardly extending end 105 of the spring is attached to the outer side wall 107 of housing 104, here shown as being hooked through an aperture 119 therein. A cam 110 (FIGS. 12 and 13) is struck out from or fixed to the surface of plate 106 opposite housing portion 104, near the outer perimeter of the plate. The cam element 110 is engaged by one leg 111 of an L-shaped cam follower lever 112 which extends through an opening 114 in a second plate 116 mounted by means of a hub 118 thereof in spaced-apart relation from plate 106, on shaft member 92. Plate 116 is fixed for rotation with shaft 92. The other leg 113 of the L-shaped lever 112 includes an enlarged, curved or offset portion 115, seen in FIG. 15, having an aperture 117 through which shaft member 92 extends. Leg 113 of lever 112 is pivotally mounted on plate 116 by complementary ears and a pivot pin 120 approximately 180 degrees from the aperture 114 through plate 116. This pivotal connection and the passing of arm 111 through aperture 114, lock lever 112 to plate 116 for rotation therewith.

Adjacent L-shaped lever 112 at the point of mounting on the shaft member 92, and separated by a washer 122, is a switch actuating lever 124 having a curved or offset forked end 125 which straddles shaft 92. At the other end 127 of the lever 124 there is a buffer 126 which engages one contact 128

of a switch having an opposed contact 130. The contacts 128 and 130 are normally out of engagement, as shown in FIG. 12. A spring 129 stretched between lever arm 127 and a fixed member biases lever 124 in a clockwise direction. Spaced from lever 124 and fixedly mounted on shaft member 92 is a worm gear or wheel 132. The worm gear 132 is mounted on shaft 92 by means of a screw or the like 33 extending through a hub 134 thereof. A worm 136 meshes with worm gear 132 and is fixed on a shaft 138 extending from an electric motor 140.

As mentioned above, meter 100 may be connected to counting mechanism 22 in a variety of ways. In FIG. 2 an alternative connection of the meter is suggested. Herein the meter 100 and its associated gear 96 and shaft 98 are connected directly to worm gear 132 with gear 96 meshing therewith. This manner of gearing in the meter 100 avoids any shock thereto which may occur with the respective gear elements 62, 64, 66 or 68 being rotated in response to the receipt of currency in the device in which the counter 20 is placed.

For purposes of affording a more complete understanding of the invention, it is advantageous now to provide a functional description of the mode in which the component parts thus far described cooperate.

Turning now to FIG. 16 of the drawings, there is shown therein a schematic diagram of a control circuit, for use in a coin operated phonograph or "juke box" or the like device. Switches 170, 172, 174 and 176 are respectively momentarily closed by the passage of five, ten, twenty-five and fifty cent pieces through the respective coin slots. Each switch operates a respective solenoid 60 of the counting device 20. Each of the switches is connected to a respective solenoid coil 171, 173, 175 and 177, and all are connected to a power source represented by a battery 180. The dollar bill circuit component 178, shown here in block form, is connected in parallel relation with the fifty cent switch 176, so that when a dollar bill is deposited in the currency receptacle adapted for receipt thereof in the phonograph, two pulses on the fifty cent solenoid 177 will occur, thus operating appropriate solenoid 60 two times, stepping the gear element 68 of counter 20 twice so as to correspond to the dollar value. Other paper bill values may be accommodated also if desired in a manner similar to that discussed.

As can be seen in FIG. 5, and as mentioned heretofore, a solenoid 60 is associated with each of the pawls 72 of the counting mechanism 22. Each of the solenoids is connected to an actuating switch 170, 172, 174 or 176 associated with a particular coin receiving mechanism or receptacle. Upon the receipt in any one of the coin receptacles of a coin of a corresponding denomination, a respective actuating switch is operated. The operation of the switch in turn momentarily actuates the appropriate solenoid 60. The operation of the solenoid moves arm 81 thereof toward the solenoid housing and in turn moves arm 75 of the pawl 72, as shown in FIGS. 6, 8, 10 and 11, in a counterclockwise direction to release tooth 79 from the peg 70 it had been holding, so that the corresponding gear may be turned as shown in the last mentioned figures, in the direction of respective arrows 145, 147, 149 and 151.

As an illustrative example, it may be assumed that receipt of a five cent piece has freed gear 62 to rotate by the rocking of pawl 72. Tooth 77 of arm 73 of the pawl limits gear element 62 to movement less than the distance between consecutive pegs until the corresponding solenoid releases and spring 74 returns pawl 73 to its rest position, thus allowing completion of rotation of gear 62 the arcuate distance between successive pegs.

The movement of the gear 62 about half-shaft 36 is effected by the turning force on ring gear 90 transmitted through pinions 84, 86 and gear 76 to half-shaft 36 and hence to pinion 56 meshing.

The rotation of ring gear 90, as can be seen in FIG. 1, allows gear 94 to turn in the direction of arrow 155 under the force of spring 102, and it in turn rotates gear 96 in the direction of arrow 157 to step the register 100 ahead, thereby to record

the deposit made in the coin operated phonograph. A similar operation takes place with the appropriate gears, etc., being involved, when a coin of a different denomination enters the appropriate coin receptacle of the device.

It is essential to the operation of the counting mechanism 22 that a driving force be provided for gear elements 62, 64, 66 and 68 when they are released by a corresponding pawl, to rotate as described above. This driving force is provided in the currency counter embodiment 20 shown herein, by the rewinding mechanism 24, shown in FIGS. 1 and 12. The rewind mechanism is a simple, efficient mechanism and is preferable over other driving force devices. However, the driving force could be provided by other suitable means, if desired.

Looking more closely at winding mechanism 24, it will be seen that gear 94, hub 93, plate 101, housing 104, and plate 106 on hub 108, are free to rotate on shaft 92. Rotation of these last-mentioned components is effected by helically wound spring 102 within housing portion 104. It is the tension provided by spring 102 which is used as the driving force to power the counting mechanism 22.

Each time a coin is received in the coin operated phonograph device and one of the gears is turned, the spring 102 partially unwinds. If the spring were allowed to unwind completely, the counting mechanism would become inoperative. Thus, this spring 102 is provided with a mechanism which operates to rewind the spring 102 once it is unwound a predetermined amount.

As shown in FIG. 12, leg 111 of lever 112 is in engagement with cam 110 mounted on plate 106. When the spring 102 reaches the above-mentioned predetermined unwound point, which occurs when gear 94 is moved a few degrees in the direction of arrow 155 and therefore every time currency is received, leg 111 will become disengaged from cam 110 and drop away therefrom. This can be seen clearly in FIG. 13 of the drawings. The lever 112 is now free to move along shaft 92 toward the housing 104. This in turn causes movement of lever 124 in a clockwise direction under the influence of spring 129 so that buffer 126 at the other end thereof moves contact 128 into engagement with contact 130. The contact pair 128; 130 serves to complete a circuit (not shown) to operate motor 140, and, in turn, through gear member 132 rotating in the direction of arrow 163, causes the shaft 92 to be rotated accordingly, rewinding helical spring 102, restoring leg 111 into engagement with cam element 110, opening contact pair 128 and 130, and replacing lever 124 at its normal position on shaft 92.

Each time currency is received in a receptacle in the coin operated phonograph, the above sequence of events takes place to step the register 100 so that it can in turn total the amount of money received in the phonograph over a period of time.

The currency counter according to the invention is so constructed that even if currency of different denominations is dropped into the coin receptacles simultaneously, the counter will function to count and total both the coins. Therefore, if a ten cent piece and a twenty-five cent piece were dropped simultaneously into corresponding currency receptacles, respective solenoids would be actuated to permit stepping of the respective gears, in this case 66, corresponding to the twenty-five cent piece, and 64 corresponding to the ten cent piece, to allow rotation of ring gear 90 and thus to register the total sum on register 100.

Thus, the currency counter 20 according to the invention provides an efficient, reliable means of correctly totaling the amount of currency received over a predetermined period of time in various types of vending or the like machines. All parts always move in the same direction, hence speeding operation and reducing noise and wear. A coin operated phonograph has been used as a preferred example of the type of device with which the currency counter 20 may be used. It is to be understood, however, that the counter according to the invention may be used satisfactorily with other vending, etc., types of devices.

Each pair of gears and meshing pinion, as 62, 64 and 56 will be recognized as a differential gear set. It will be understood that differential gear sets with different types of teeth could be used, or a friction gear drive could be substituted for the toothed gear drive with some possible loss of accuracy that might creep in through slippage. In any event, in the ensuing claims it is to be understood that the term gear includes friction as well as toothed drives.

It is important that a continuous impositive driving force is applied to the ring gear and that it be capable of producing an indefinite number of revolutions. The spring motor shown with the electric motor winding the spring is one effective way of achieving this end, but it will be understood that other means could be used. For example, a spring could be wound with a solenoid and pawl-and-ratchet mechanism, or a pneumatic motor could be substituted for the spring motor.

While a particular embodiment of the invention has been shown, it is to be understood, of course, that the invention is not limited thereto since many modifications may be made.

I claim:

1. Currency counting apparatus comprising: support means, rotatable shaft means mounted on said support means, a register and means connecting said rotatable shaft means to said register for driving said register in response to the rotation of said shaft means, said means including a plurality of gear elements mounted for rotation on said shaft means, each of said gear elements corresponding to a different value of currency deposited in a currency receiving mechanism, connected to said apparatus, means providing for the rotation of each said gear element on said shaft means a respective, predetermined number of degrees for each deposit in said receiving mechanism of currency of a corresponding value, means coupling said gear elements with said shaft means for effecting rotation of said shaft means a corresponding number of degrees in response to the rotation of said gear elements on the latter, said coupling means includes at least one pinion rotatably mounted on a transverse shaft fixed on and extending radially outwardly from said shaft means, said one pinion being in meshing engagement with at least one of said gear elements so that upon the rotation of said one gear element, said pinion, in response thereto, causes a corresponding rotation of said shaft means, and further including at least one gear member fixedly mounted on said rotatable shaft means so as to be rotatable therewith, and a ring gear member having a plurality of pinions mounted at the inner perimeter thereof and extending inwardly toward the center of the ring gear member, said ring gear member being mounted coaxially with said one gear member with said pinions of said ring gear member meshing with said gear member, so that upon rotation of said shaft means, said gear member is likewise rotated, causing, through said pinions, a corresponding rotation of said ring gear member.

2. Currency counting apparatus as claimed in claim 1 wherein said register includes a rotatable shaft and a gear connected thereto, and wherein said gear of said register is in meshing engagement with said register member, whereby upon the rotation of said ring gear member, said register, through said gear and shaft, is operated to total the amount of currency deposited in said receiving mechanism.

3. Currency counting apparatus comprising: support means, rotatable shaft means mounted on said support means, a register and means connecting said rotatable shaft means to said register for driving said register in response to the rotation of said shaft means, said means including a plurality of gear elements mounted for rotation on said shaft means, each of said gear elements corresponding to a different value of currency deposited in a currency receiving mechanism connected to said apparatus, means providing for the rotation of each said gear element on said shaft means a respective, predetermined number of degrees for each deposit in said receiving mechanism of currency of a corresponding value, means coupling said gear elements with said shaft means for effecting rotation of said shaft means a corresponding number of

degrees in response to the rotation of said gear elements on the latter, said shaft means includes a pair of shafts, independently mounted for rotation on said support means and being in axial alignment, with first ends being adjacent each other, wherein each said shaft includes, mounted rotatably thereon, at least one pair of gear elements, each gear element representing a different denomination of currency, and at least one pinion rotatably mounted on a transverse shaft fixed on and extending outwardly from each of said pair of shafts and being in meshing engagement with a respective pair of gear elements, so that upon the rotation of one or both of said gear elements of one or both of said pairs, a respective pinion is caused to rotate said corresponding shaft in response thereto.

4. Currency counting apparatus as claimed in claim 3 wherein said drive means includes a first and second gear member, said first gear member being mounted at said first end of a first one of said pair of shafts and said second gear member being mounted at said first end of the second one of said pair of shafts, each said gear member being rotatable with a corresponding shaft, and a ring gear member including a plurality of pinions mounted at the inner perimeter thereof and extending inwardly toward the center of the ring gear member, said ring gear member being mounted coaxially with and between said first and second gear members, with said pinions being in meshing engagement with said gear members, so that, upon the rotation of one of said shafts, a corresponding gear member is rotated therewith, thereby through said pinions of said ring gear member to rotate said ring gear member correspondingly.

5. Currency counting apparatus comprising: support means rotatable shaft means mounted on said support means, a register and means connecting said rotatable shaft means to said register for driving said register in response to the rotation of said shaft means, said means including a plurality of gear elements mounted for rotation on said shaft means, each of said gear elements corresponding to a different value of currency deposited in a currency receiving mechanism connected to said apparatus, means providing for the rotation of each said gear element on said shaft means a respective, predetermined number of degrees for each deposit in said receiving mechanism of currency of a corresponding value, and means coupling said gear elements with said shaft means for effecting rotation of said shaft means a corresponding number of degrees in response to the rotation of said gear elements on the latter, each of said gear elements including, extending outwardly from one surface thereof, a predetermined number of pegs, corresponding to the value of currency represented by said gear element, said pegs being angularly spaced at the outside perimeter of each of said gear elements, and wherein said apparatus further includes a plurality of pawls, for operating each said gear element, and being pivotally mounted on said support means, each said pawl including a spring, a first end of said spring being connected to said pawl and a second end being connected to said support means, each of said pawls, due to the tension of a corresponding spring, normally engaging one of said pegs of a respective gear element, and pawl operating means connected to each said pawl for operating said respective pawls against the tension of said spring upon the depositing in said receiving mechanism of a corresponding value of currency, said pawl upon the operation of a corresponding operating means, releasing said one peg to allow the corresponding gear element to rotate the distance between pegs, whereby said pawl is moved back to a normal position by said spring to reengage the next consecutive one of said pegs.

6. Currency counting apparatus as claimed in claim 5 wherein each of said pawls includes a first and second arm being rigidly interconnected at first ends thereof, the second, free ends of said arms each including a tooth member extending therefrom, wherein a corresponding pawl spring is connected at a first end thereof to said second arm of a respective pawl, causing the tooth member of said second arm to engage one of said pegs of a respective gear element and wherein said operating means includes a solenoid having a movable arm

portion connected to said second arm of said pawl, said solenoid being operable against the tension of said pawl spring in response to the depositing of a corresponding value of currency in said currency receiving mechanism, said tooth member of said first arm of said pawl engaging a second one of said pegs of a respective gear element upon the operation of said solenoid to prevent over rotation of said gear element.

7. Currency counting apparatus as claimed in claim 6 and further including a first, second, third and fourth gear element, said first gear element representing five cent pieces, having ten pegs and rotating the distance between consecutive pegs for each five cent piece received in said receiving mechanism, said second gear element representing ten cent pieces, having five pegs and rotating the distance between consecutive pegs for each ten cent piece received in said receiving mechanism, said third gear element representing twenty-five cent pieces, having two pegs and rotating the distance between consecutive pegs for each twenty-five cent piece received in said receiving mechanism, and said fourth gear element representing fifty cent pieces, having one peg and rotating one revolution for each fifty cent piece received in said receiving mechanism.

8. Currency counting apparatus comprising: support means, rotatable shaft means mounted on said support means, a register and means connecting said rotatable shaft means to said register for driving said register in response to the rotation of said shaft means, said means including a plurality of gear elements mounted for rotation on said shaft means, each of said gear elements corresponding to a different value of currency deposited in a currency receiving mechanism connected to said apparatus, means providing for the rotation of each said gear element on said shaft means a respective, predetermined number of degrees for each deposit in said receiving mechanism of currency of a corresponding value, and means coupling said gear elements with said shaft means for effecting rotation of said shaft means a corresponding number of degrees in response to the rotation of said gear elements on the latter, and means connected to said drive means for providing to said counter a driving force, said driving force means being self-restoring, thereby to continuously cause said counter to be operable.

9. Currency counting apparatus as claimed in claim 4 and further including a winding mechanism, said winding mechanism including a rotatable shaft member having mounted thereon a gear member, said gear member being in meshing engagement with said ring gear member, spring means mounted on said shaft member and providing a driving force to said ring gear member, and motor means connected to said shaft member, whereby upon the rotation of said ring gear member in response to the deposit of currency in said receiving mechanism, said spring means is partially unwound, said motor means, through said shaft member, being operable to rewind said spring means.

10. Currency counting apparatus as claimed in claim 9 wherein said spring means includes a helical spring mounted at one end to said shaft member and a spring housing mounted for rotation about said shaft member, the other end of said spring being connected to said housing, and wherein said rewinding mechanism further includes a cam member mounted on said housing, an L-shaped cam follower mounted at one leg to said shaft member and the second leg thereof engaging said cam member, and contact means connected to said shaft member adjacent said one leg of said L-shaped cam follower, said contact means operable to actuate said motor means, and being normally in an open condition, whereby, upon the rotation of said gear member in response to said ring gear member being rotated, said shaft member in turn is rotated causing, through said helical spring member, a rotation of said housing in a direction causing said spring member to unwind so that said second leg of said strip is dislodged from said cam member, and said contact means in response thereto is actuated to operate said motor means, thereby to turn said shaft member, rewinding said spring and restoring said cam

member of said housing and said second leg of said cam follower to reengage.

11. Currency counting apparatus as claimed in claim 7 wherein, upon the receipt in said currency receiving mechanism of a one dollar deposit, said currency control causes said solenoid associated with said fifty cent gear element to be rotated twice the distance rotated upon the receipt of a fifty cent piece.

12. Currency counting apparatus comprising: support means, a first and second shaft, each being independently mounted for rotation on said support means, said shafts being in axial alignment with first ends thereof being adjacent each other, each shaft including a first and second gear element rotatably mounted thereon, the first and second gear element of said first shaft representing a five and ten cent piece, respectively, and the first and second gear element of said second shaft representing a twenty-five and fifty cent piece, respectively, a pinion rotatably mounted on a transverse shaft fixed on and extending radially outwardly from between and in meshing engagement with said first and second gear elements of a corresponding shaft, a first gear member fixedly mounted on the first end of said first shaft for rotation therewith and a second gear member fixedly mounted on the first end of said second shaft for rotation therewith, a ring gear member including at least one pinion mounted at the inner perimeter thereof and extending inwardly toward the center of the ring gear member, said ring gear member being mounted coaxially with and between said first and second gear members with the pinions thereof meshing with said first and second gear members, and a summing register coupled to said ring gear member, whereby upon the deposit of currency in a receiving mechanism connected to said apparatus, a gear element corresponding to the denomination of said deposited currency is rotated a predetermined number of degrees on a respective shaft so that the corresponding pinion, fixedly mounted on said shaft, rotates said shaft in response thereto, in turn rotating a respective gear member, thereby to rotate said ring gear member, to operate said summing register.

13. Currency counting apparatus as claimed in claim 12 wherein each of said gear elements includes a predetermined number of pegs being angularly spaced about said gear element and extending outwardly therefrom and corresponding to the denomination of currency represented by said gear element and wherein said counting apparatus further includes a plurality of pawls, each one of which is adapted for operation with a respective gear element and which is pivotally mounted on said support means and normally engaging one of said pegs of a respective gear element, and a plurality of solenoids, one of which is connected to each of said pawls, whereby upon the deposit of a denomination of currency in said receiving

mechanism, a corresponding one of said solenoids is actuated to operate a respective pawl, thereby to release said one peg, allowing said gear element to rotate on a corresponding shaft the distance between said one peg and the one following thereafter, in the direction of rotation of said gear element.

14. Currency counting apparatus as claimed in claim 13 wherein said apparatus further includes a control circuit for operating said solenoids, said control circuit including means responsive to the receipt in said receiving mechanism of a one dollar deposit to operate twice in succession the solenoid operating said fifty cent piece gear element, thereby to rotate said fifty cent piece gear element correspondingly, to in turn record said deposit on said summing register.

15. Currency counting apparatus comprising: base means; a shaft rotatably supported from said base means; means constantly tending to turn said shaft; and escapement means for said shaft; said escapement means including a differential gear set having a pair of gears mounted coaxially about said shaft and free to turn relative thereto and relative to one another and a pinion meshing with said gears and rotatable about an axis transverse of said shaft, said axis being fixed for turning with said shaft, a first plurality of protuberances on one of said gears in equal arcuate spaced relation thereon and each corresponding to a first unit of money, a second and different plurality of protuberances on the second of said gears in equal arcuate spaced relation and corresponding to a second unit of money, a first releasable stop sequentially engageable with said first protuberances, means for releasing said first stop upon receipt of a first unit of money in a connected mechanism, a second releasable stop sequentially engageable with said second protuberances, means for releasing said second stop upon receipt of a second unit of money, such release of said first and second stops permitting said shaft to turn predetermined corresponding increments; a register; and means connecting said register to said shaft for rotation therewith.

16. Currency counting apparatus according to claim 15 and further including: a second shaft coaxial with said first shaft in end-to-end relation thereto; a second differential gear set similar to the one recited having third and fourth gears respectively with a third and a fourth plurality of protuberances thereon corresponding to third and fourth units of money; the shaft turning means comprising a third differential gear set having a pair of gears respectively fixed on said shafts and a pinion meshing with said last-mentioned pair of gears, and means tending to orbit said pinion about said shafts.

17. Currency counting apparatus according to claim 16 and wherein said shaft turning means further includes a ring concentric with said shafts and carrying said pinion, and impulsive means tending to turn said ring.
